UNITED STATES PATENT OFFICE

137,867

DESIGN FOR A CASING FOR WRITING IMPLEMENT OR THE LIKE

Raymond Loewy, New York, N. Y., assignor to Eversharp, Inc., Chicago, Ill., a corporation of Delaware

Application November 6, 1943, Serial No. 111,612

Term of patent 14 years

(Cl. D74—17)

To all whom it may concern:

Be it known that I, Raymond Loewy, a citizen of the United States, residing at New York, in the county of New York and State of New York, have invented a new, original, and ornamental Design for a Casing for Writing Implement or the Like, of which the following is a specification, reference being had to the accompanying drawing, forming a part thereof.

In the drawing:

The figure is a side view of a casing for writing implement or the like showing my new design as viewed slightly in perspective from one end.

The characterizing features of my new design are shown in full lines and appear substantially the same on any side.

I claim:

The ornamental design for a casing for writing implement or the like, substantially as shown and described.

RAYMOND LOEWY.
